UNITED STATES PATENT OFFICE.

FREDERICK J. GIBSON, OF OAKLAND, CALIFORNIA.

AMUSEMENT DEVICE.

1,107,287.

Specification of Letters Patent. Patented Aug. 18, 1914.

Application filed April 29, 1914. Serial No. 835,176.

To all whom it may concern:

Be it known that I FREDERICK J. GIBSON, a citizen of the United States, residing at Oakland, in the county of Alameda and 5 State of California, have invented certain new and useful Improvements in Amusement Devices, of which the following is a specification.

This invention relates to improvements in 10 amusement devices and has for its principal object the construction of a novel device of the character named wherein the users will in a measure experience the sensations of an aeroplane ride.

15 One of the principal objects of my invention is to provide a car shaped like an aeroplane, which moves in a circle and by means of suitable mechanisms is given a rocking and a vertical motion.

20 Another object is to provide ailerons, which are connected to a controlled mechanism located adjacent the seat so that the occupants may impart a limited lateral movement to the body of the aeroplane, 25 which movement is resisted by strong springs.

With these and other objects in view my 30 invention consists in the novel construction and arrangement of parts as herein described and more specifically pointed out in the annexed claims.

Reference should be had to the accompanying drawings forming a part of this specification wherein,

35 Figure 1 is a view in plan of my improved amusement device. Fig. 2 is a view in section showing the manner of supporting the revolving frame of producing the vertical movement of the aeroplanes and 40 means for producing the lateral movement thereof independent of the control through the ailerons. Fig. 3 is a slightly enlarged view in side elevation of one of the aeroplanes or carriages used on the device. Fig. 45 4 is an enlarged plan view of the frame work used in supporting the carriages. Fig. 5 is an enlarged view in plan of one of the aeroplanes or carriages with certain parts 50 broken away for which to illustrate the mechanism for producing lateral movement

of the aeroplanes. Fig. 6 is an enlarged view in rear elevation disclosing in more detail the mechanism for governing the ailerons. Fig. 7 is an enlarged view in section on 7—7 Fig. 2. Fig. 8 is an enlarged view in 55 plan of a portion of the under structure of my improved device.

Referring to corresponding parts by the same numerals of reference throughout the several views, 1 denotes a suitable foundation having attached in the upper surface thereof a base plate 2, wherein is held a stub shaft 3 about which is pivotally mounted a hub 4, and to the latter are fastened the radial arms 5, held in spaced relation by 60 means of certain members 6, 7 and 8 forming cords between the arms. On members 7 at suitable intervals are attached frames 9 wherein are pivotally mounted flanged wheels 10 adapted to run on a circular rail 65 11, supported on a foundation 12. Upon the member 6 is attached a bevel gear 13, and the foundation 1 is provided with an extension 14 whereon is bolted an electric motor 15 having on its shaft a beveled pinion 16 70 75 adapted to mesh with the gear 13 and thus impart a rotary motion of the frame work.

The aeroplanes or carriages denoted in general by 20 may be of any preferred construction, some representing monoplanes and 80 some biplanes, although I have exclusively illustrated the biplanes in connection with my device. These planes are provided on the underside with bearings 21 through which extends a shaft 22, which is held in 85 the heads 23 formed on the upper end of the vertical rods 24. A circular platform 25 is formed around the outer edge of the arms 5 and under each plane is an opening 26, in which is pivotally mounted a plate 27 provided on each end with a stub shaft or pin 28 mounted in bearings 29 on the platform, thus permitting the plate to have a lateral 90 rocking movement in relation to the platform. Formed integrally with this plate adjacent to each end are sleeves 30 wherein the rods 24 are slidably mounted and the lower ends of the latter are attached to a plate 31, which is provided with a central opening 32, and on each side thereof are bearings 33. A 95 100

wheel 34 is mounted in this opening having a shaft 35 journaled in the bearings 33 and below this wheel is provided a trough shaped channel 36, in which the wheel rests, 5 this channel being provided with certain inclined portions 36' thus raising the wheel and imparting up and down movement to the rods 24. The channel is also curved out of alinement as at 37, thus causing the rods 10 24 to be inclined and the plate 27 to be rocked in the bearings 29.

The occupant's seat is denoted by 40 and 41 is a foot rest in connection therewith. A hand lever 43 is pivotally mounted on the 15 foot rest and to the lower end of the lever are attached cords 45 and 46 extending over suitable pulleys 44 to the ailerons 47 in the usual manner so that one is raised when the other is lowered.

20 In operation it will be apparent that when the motor 15 is started, a rotary movement will be imparted to the platform, carrying the aeroplanes in a circular path. As they move around this path the track 36 being 25 provided with vertical as well as horizontal curves and up and down movement is imparted to the carriages as well as a lateral rocking movement throughout the pivots 28. In addition to this movement the occupants 30 by the use of the hand lever 43 may impart other lateral movements about the shaft 21. This lateral movement is resisted by a heavy double spring 23' having one end attached to the rods 24 and the other end resting 35 against the underside of the aeroplanes. These springs normally hold the latter in a horizontal position and tend to resist the rocking movement caused by the use of the ailerons.

40 It will thus be seen that I have provided an amusement device of novel construction and which will appeal to the people owing to its likeness to an aeroplane. While I have shown the preferred embodiment of my in- 45 vention it will be understood that minor changes may be made in detail of construction without departing from the scope of the claims.

What I claim is:—

- 50 1. In an amusement device of the character described comprising a circular revolu- 55 ble platform, a plate pivotally mounted in said platform tangential to the direction of rotation, tubular sleeves adjacent each end of said plate, rods slidably mounted in said sleeves, a bearing plate connecting the lower ends of said rods, a wheel pivotally mounted in said bearing plate and a grooved track adapted to receive said wheel.
- 60 2. In an amusement device of the character described comprising a circular plat- 65 form, means for imparting rotation thereto, a plurality of plates pivotally mounted in

said platform tangential to the direction of rotation, a plurality of rods slidably mounted in each of said plates perpendicular to the surface thereof, an aeroplane shaped carriage oscillatively mounted on the upper ends of said rods, ailerons mounted on said carriages and means adjacent the occupant's seat for controlling said ailerons. 70

3. In an amusement device of the character described comprising a circular plat- 75 form, means for imparting rotation thereto, a plurality of plates pivotally mounted in said platform, rods slidably mounted in said plates perpendicular to the surface thereof, bearings on the upper end of said rods, a shaft oscillatively mounted in said bearings, a carriage rigidly attached to said shaft and spring means for maintaining said carriages in a normally horizontal position. 80

4. An amusement device of the character described comprising a circular revoluble platform, a plurality of frames mounted 85 thereon, carriages pivotally mounted on said frames, spring means for holding said carriages in a horizontal position and planes controlled from the seat of the carriage for imparting a lateral swaying movement to 90 said carriages.

5. In an amusement device of the character described comprising an aeroplane shaped carriage, rods having said carriage pivotally mounted on the upper end thereof, 95 a revoluble platform, plates pivotally mounted therein, said rods slidably mounted in said plates, a bearing plate attached to the lower end of said rods below said platform, a wheel pivotally mounted in said bearing plate, a track adapted to receive said wheel, vertical raises in said track for imparting a vertical movement to said carriages, and lateral curves in said track for imparting a lateral movement to said carriage supporting frame about said pivots of said plate. 100

6. In an amusement device of the character described comprising a circular revoluble platform, a plurality of frames mounted thereon, said frames pivotally mounted in said platform, aeroplane shaped carriages pivotally mounted in the upper end of said frames, ailerons on said carriages, means for operating said ailerons adjacent the occupant's seat, and spring means for resisting the oscillating movements caused by said ailerons. 110

7. In an amusement device of the character described comprising a circular plat- 120 form, a circular track on which said platform is adapted to rotate, a second track having portions out of alinement with the circular path of the platform and other portions vertically inclined, frames pivotally mounted in said platform, a wheel carried 125

by the lower end of said frame and adapted to coact with said last mentioned track, rods forming a portion of said frame and being slidably mounted in the pivoted portion of said frame, a carriage pivotally mounted on the upper ends of said rods, spring means holding said rod normally horizontal and ailerons on said carriages actuated by means

adjacent the occupant's seat for imparting a lateral movement to said carriage. 10

In testimony whereof I affix my signature in presence of two witnesses.

FREDERICK J. GIBSON.
